SPRING GRIP TABLE

Roy S. Sanford, Woodbury, Conn., assignor to
The Autoyre Company, Incorporated, Oakville,
Conn., a corporation of Connecticut

Application June 26, 1948, Serial No. 35,328

2 Claims. (Cl. 311—110)

1

This invention relates to a table construction and to a subassembly structure which is useful for fabricating tables.

This invention has particular reference to a table structure and a table subassembly which is of all metal construction and which is adapted firmly to support a flat top member which may be formed of glass or other suitable material. An object of this invention is the provision of a table structure which may be readily and inexpensively constructed on a mass production basis.

A further object of this invention is the provision of a rigid table structure in which the top member may be readily removed for cleaning or other purposes.

A still further object of this invention is the provision of a table structure wherein the top member is removably supported by resilient means.

A still further object of this invention is the provision of a metal table subassembly which may conveniently be plated in the usual type plating bath and thereafter assembled by welding in such a manner that the welding marks are concealed.

Further and additional objects will appear from the following description, the accompanying drawings and the appended claims.

In carrying out this invention in one form there is provided a table which comprises a base portion, a top member spaced from the base portion and top support members extending from the base portion to spaced points adjacent the peripheral area of the top member. The top support members are provided with downwardly extending reverse bend portions, each of which forms a leg for the table, and the top support members are further provided with top member securing means adjacent the upper ends thereof. In a preferred form of the invention, the several top support members extend generally upwardly in diverging relationship and the upper ends thereof are resiliently tensioned toward each other in order to hold the top member securing means in top member engaging relationship. The upper ends of the top support members are preferably bent into a substantially horizontal plane, thus providing side edges upon which the top member may rest, and the top securing means or top grip members may take the form of plates welded or otherwise secured to the end surfaces of the top support members which plates extend across the underside of the corner portions of the top member, said plates having upwardly and inwardly extending wings or strap members which serve to embrace the corners of the top

member whereby to hold it in a desired position.

In accordance with a further embodiment of this invention, the table of this invention may be formed from two or more subassemblies and connectors therefor. Each of these subassemblies comprises a resilient rod member formed in substantially the shape of a U, having coplanar side members and having a base member secured between the lower ends thereof by reverse bend portions. The two side members of each U-shaped subassembly form a pair of the top support members for the table and the two reverse bend portions of each subassembly form a pair of the legs for the table. Preferably the reverse bend portions are so formed that the base member lies in a plane spaced from the common plane of the side members so that the base members of two or more subassemblies may be secured together by suitable connectors or cross members in such a manner that a base portion is provided having an area somewhat smaller than the area of the top member. Thus the reverse bend portions forming the legs of the final table extend in planes which intersect a central area of the top member and provide means for tensioning of the upper ends of the top support members toward the central area of the top member whereby a firm securement of the top member in a desired position is achieved when the table is assembled.

For a more complete understanding of this invention, reference will now be made to the accompanying drawings, wherein

Fig. 1 is a perspective view of a table constructed in accordance with one embodiment of this invention;

Fig. 2 is a top plan view of a modified form of table;

Fig. 3 is a broken sectional view taken along the line 3—3 of Fig. 2;

Figs. 4 through 8 are detail views of the table shown in Figs. 2 and 3;

Fig. 9 is a plan view of another modified form of a table constructed in accordance with this invention;

Fig. 10 is a broken side elevational view of the table shown in Fig. 9; and

Figs. 11 through 16 are detail views of various elements of the table shown in Figs. 9 and 10.

With particular reference now being made to Fig. 1, there is shown a table having a square top member 20 which may be formed of glass or other suitable material. The table top member 20 is supported by a plurality of resilient top support members 22 which extend generally

downwardly in converging relationship, terminating at their lower portions in reverse bends 24 which provide legs for the table structure. The reverse bend portions 24 extend upwardly and inwardly and are engaged with a base portion 26, this base portion being formed by base members 28 and cross members or connectors 30 which are welded or otherwise secured together.

It will be noted that a pair of top member supports 22, a pair of reverse bend portions 24 and one base member 28 are formed from a single substantially U-shaped piece which is in the form of a resilient metallic rod having a square cross section. The sides 22 of each U-shaped piece are coplanar and the base member 28 lies parallel to but outside of the plane of the sides 22. As shown in Fig. 1, a pair of these substantially U-shaped rods are secured together by a plurality of connectors 30, thus forming an integral unit. The upper portions of the top support members 22 are provided with a plurality of top grid members 32 which may be secured to the support members in any desired manner (for example as described in the modifications shown in Figs. 2 through 16) and these top grip members embrace the corners of the top member 20. As above indicated, the U-shaped rod sub-assembly is resilient in nature and the upper ends thereof are tensioned toward a central area of the top member 20 and, accordingly, the top is supported on top of the members 22 and resiliently held in place by the top grip members 32. In order to separate the top from the table, it is only necessary to spring the tops of a pair of the supports 22 in an outward direction to free the corresponding grips 32 from top-engaging relationship and thereafter the top may be readily lifted for cleaning or other purposes as desired.

This table may be readily fabricated and after the various elements of the base portion and the table top support members have been assembled as indicated, the entire unit (except the glass top) may be placed in a plating bath in order to provide a suitable metallic coating thereon. However, the assembled table may be somewhat difficult to handle in the usual form of plating bath because of its size and accordingly it may be desirable separately to plate the several elements prior to the time that they are assembled in final relationship. Such a procedure is contemplated in the additional embodiments of this invention which are about to be described.

Reference is now made to the form of table disclosed in Figs. 2 through 8. Generally speaking, this modification has the same over-all shape as the table disclosed in Fig. 1 and comprises a base portion 34, top support members 36 and reverse bend portions 38 integral with and extending between a base member 40 and the support members 36. The upper ends of each of the top support members 36 are provided with outwardly bent portions 42 upon which the top 44 of the table is adapted to rest adjacent the corners 46 thereof. Top grip members 48 are welded or otherwise secured to the end edges of each of the top support members 36 and such top grid members comprise, in the modification shown, a plate member 50 extending across and underneath the corner 46 of the top member 44, and upwardly and inwardly extending integral wings 52 which serve to embrace the top member 44 at the several corners.

The base portion 34 of the table shown in Figs. 2 through 8 comprises the base members

40 having C-shaped connector rods 56 secured therebetween as by welding or other means. As shown, the rods 56 are preferably spot-welded to the base members 40 in recesses 54 or other cut-out portions in the members 40 forming enlarged contact surfaces for the welds, thus providing increased strength in the completed structure.

In order to fabricate and assemble the table disclosed in Figs. 2 through 8, the table grip members 48 are welded or otherwise secured to the upper ends of the U-shaped rods which form the base, legs and support members for the table. Thereafter the resulting subassembly is plated. The connectors 56 are likewise formed and plated. Thereafter the connectors and a pair of subassemblies are welded together in the position indicated in Figs. 2 and 3. The weld marks on the connectors 56 and the base members 40 are then concealed by channel-shaped snap covers 58 having the construction indicated in Figs. 7 and 8. Thereafter a glass top 44, in this instance square, defined by corners 46 enclosing an area somewhat larger than that defined by the ends of the top support members 36, is placed in position by resiliently springing the upper ends of the top support members in an outward direction. The resiliency is provided at least in part by the reverse bend portions 38 forming the legs of the table. After the top member 44 is in place, the resilient tensioning of the upper ends of the top support members toward the central area of the top serves to secure the top member firmly in position on the table. The elements constituting the base portion 34 lie in substantially a flat plane and provide a surface underneath the top member on which books, magazines or other articles may be supported. It will be apparent that Figs. 2 and 3 showing views of this modification do not have the snap covers 58 in place and their structure and mode of attachment are indicated in Figs. 7 and 8.

A further modification of this invention is that structure disclosed in Figs. 9 through 16 of the drawings. The structure disclosed in these figures is very similar to that disclosed above in Figs. 2 through 8 except that the top securing means and the base portion are modified somewhat. With respect to the top securing means, each comprises a plate 60 welded or otherwise secured to an end edge of the upper portion of a top support member 62. A U-shaped strap member 64 is secured to the opposite ends of each plate 60 and extends across the upper surface of the corner of the table, thereby defining an aperture through which the corner may be inserted. Preferably the base 66 of the U-shaped strap member 64 is curved inwardly to permit a relatively large portion of the peripheral area of the top member to lie under the strap base. This form is particularly desirable if it is desired to employ a round table top instead of a top having corners as shown.

The base of the modification shown in Figs. 9 and 16 is similar to that modification previously described except that here the cross members or connectors 68 are four in number and are secured by welding or otherwise to the underside of the base members 70. Suitable recesses 72 are provided in the base members 70 in order to provide an extended surface for welding or otherwise securing the connector 68 thereto.

The table disclosed in Figs. 9 through 16 may be assembled in the same manner as that in the modification disclosed in Figs. 2 through 8.

After a pair of subassemblies and connectors have been plated and then secured together by welding in the position shown, the weld marks may be concealed by suitable plated snap covers 14 of the character disclosed in Figs. 9, 10, 13 and 14.

It will be apparent from the foregoing description that a table has been provided which is lightweight, durable, and which may be readily manufactured in large quantities. The separate units or subassemblies may first be formed and plated and thereafter assembled in the completed unit in such a manner that the weld marks will not be visible on the plated surfaces. The table has many uses which will readily be apparent to one skilled in the art.

In the drawings there have been shown modifications which indicate a table of the square type. However, it will be readily apparent that the invention may be applied to rectangular tables or polygonal-shaped tables having three or more sides or corners. Also if desired, the table top may be circular or elliptical in shape and still come within the contemplation of this invention.

While several particular embodiments of this invention are shown above, it will be understood, of course, that the invention is not to be limited thereto, since many modifications may be made, and it is contemplated, therefore, by the appended claims, to cover any such modifications as fall within the true spirit and scope of this invention.

I claim:

1. A table comprising a pair of substantially U-shaped members each having a base member, upwardly and divergently extending coplanar resilient side members, and reverse bends in the lower portions of said side members forming legs

for said table, said U-shaped members being disposed on opposite sides of the vertical axis of said table; top edge embracing means adjacent the upper ends of said side members; a top member having edges received in said embracing means, the upper ends of said side members being spread apart to receive said top edges within said embracing means whereby said embracing means are tensioned toward a central area of said top member; and cross members rigidly secured between said base members to form therewith a base portion for said table.

2. The table recited in claim 1 wherein said base member of each U-shaped member is spaced from the plane defined by said side members and inwardly toward the vertical axis of said table.

ROY S. SANFORD.
